US00D989841S

(12) **United States Design Patent** (10) Patent No.: **US D989,841 S**
(45) Date of Patent: **** Jun. 20, 2023**

(54) **CAMERA**(71) Applicant: **GoPro, Inc.**, San Mateo, CA (US)(72) Inventors: **John George Muhlenkamp, IV**,
Brisbane, CA (US); **Daniel J. Coster**,
Oakura (NZ); **Huy Phuong Nguyen**,
Alpine, UT (US); **Kielan C. Crow**, San
Mateo, CA (US); **Nicholas Vitale**,
Foster City, CA (US)(73) Assignee: **GoPro, Inc.**, San Mateo, CA (US)(***) Term: **15 Years**(21) Appl. No.: **29/847,169**(22) Filed: **Jul. 21, 2022**

(56)

(57) CLAIM

The ornamental design for a camera, as shown and described.

DESCRIPTION

FIG. 1 is a top, front, and right side perspective view of a camera showing our new design;

FIG. 2 is a bottom, rear, and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the camera in which the design is embodied that form no part of the claimed design.

1 Claim, 8 Drawing Sheets
